ABSTRACT OF THE DISCLOSURE

Discloses a rotating receiving, classifying and propelling member for use with an icemaking machine of the type having vertically extending tubes for conducting downwardly flowing water to be frozen into ice under the influence of a refrigerant surrounding the tubes so as to form solid or hollow ice rods inside the tubes. The rotating receiving, classifying and propelling member receives sized pieces of ice cut from the rods by a revolving knife and consists of a series of radiating ribs each of which extend outwardly and rearwardly to the periphery of the member. In combination therewith is a deflector member extending across said receiving member in proximity to a discharge port, said deflector coacting with the revolving member to produce a reaction force which is exerted on the cut ice cylinders to propel them through a curved path defined by said ribs selectively to a discharge port at the periphery of the rotating circular member.

This invention relates to a rotary receiving, classifying and propelling device to be used with an icemaking apparatus such as is disclosed in Kubauh Patent No. 2,239,234 granted Apr. 22, 1941. In this type machine, which is in wide commercial use, ice in cylindrical form is manufactured in a bundle of upright externally refrigerated tubes by the flow of water through said tubes. The ice forms by accretion on the inner walls of the tubes, the thickness of ice being dependent upon the length of the freezing period. Normally the freezing cycle is such that the ice cylinders do not freeze completely which results in a hollow ice rod. Thus cold water continuously flows through the tubes and insoluble impurities are washed out of the ice as it forms by accretion on the walls of the tubes. This produces a clear, transparent, ice rod without an opaque center core. At the end of the freezing period the outer surface of the ice cylinder is thawed by admission of hot refrigerant to the apparatus, so as to break its adherence to the walls of the tube. It therefore slides gravitationally from the lower end of said tube into engagement with a support above which a revolving knife progressively severs the ice cylinder into small units or pieces.

Despite the fact that the severed pieces are in reality cylindrical in form with a center aperture, they are often referred to as "ice cubes" or cylinders. These "cubes" or cylinders are stored in a bin from which they are withdrawn as needed.

It will be appreciated that the revolving knife or severing member produces, in addition to the severed cubes, ice chips and fragments, which are referred to in the trade as "fines." When the severed cubes are stored, the undersized pieces of ice and fines tend to sift into the interstices between cubes and freeze or pack, thus producing two or more cubes frozen together rather than discrete cubes, as desired.

It is an object of this invention to provide a classifying means for the severed cubes which will classify and separate the cubes from the fines.

It is another object of this invention to provide a means

2

which will propel the classified ice cubes to a desired point for discharge from the unit.

Still another object of this invention is a support plate which will receive, classify and propel the severed ice cubes so as to prevent bridging or packing of the ice cubes in storage.

Still another object of this invention is a method and means whereby the ice chips and fines will be delivered to the cold water tank so the latent heat of fusion of the ice will be advantageously used in precooling water for the further production of ice cubes.

Basically my invention involves the provision of a circular receiving member which is rotatably driven to classify and propel the ice cubes laterally toward a chute. The receiving member consists of a hub having a series of ribs radiating therefrom so that each rib curves outwardly and rearwardly to the periphery of the circular member. The spacing of the ribs is such that the distance between the ribs at any particular point is less than the minimum outer dimension of the ice cubes so that the ribs act as tracks to propel the cubes through a path terminating at the edge of the member. The ribs are so arranged that the cubes are retained thereon and are driven through a path defined by said ribs to a discharge port. In the process of moving through this path (laterally and rearwardly, relative to the direction of the rotatively driven circular member), the ice chips and fines fall through the space between the ribs into the cold water tank so that the latent heat of fusion of the ice is available to precool the water in the cold water tank further for recycling to the icemaking stage. In combination with the circular receiving plate is a deflector fixedly mounted across said receiving plate between the hub and the upper edge of said discharge port, which coacts with said rotating circular member to produce a reaction force which is impressed on said cut ice cylinders to selectively propel or force said regular size ice pieces through said path defined by said ribs to said discharge port and to gravitationally separate said undersize ice pieces therefrom.

The invention will be better understood by reference to the accompanying drawings in which

FIG. 1 is a perspective view, partly in section, of a portion of an icemaking machine incorporating the invention.

FIG. 2 is a vertical diametrical sectional view of part of FIG. 1 with parts in elevation.

FIG. 3 is a plan view of the receiving, classifying and propelling device of this invention.

FIG. 4 is a fragmentary plan view of a modified receiving, classifying and propelling member which illustrates the relation of the deflector thereto.

FIG. 5 is a fragmentary side elevation illustrating the relation of the ribs of the receiving, classifying and propelling member to the ice cube.

Referring now to the drawings, in FIGS. 1 and 2, the outer jacket 1 of a freezer or evaporator has tubes 2 extending through a bottom plate or tube head 3. The upper end of the freezer may be similarly constructed and as the freezer and water supply are of conventional construction, they are not further illustrated. In the freezing phase of operation a liquid refrigerant is supplied to the jacket surrounding tubes 2 and water flows down the inside walls of tubes 2 and freezes thereon, excess water being discharged at the bottom of the tubes and flowing into cold water tank 45 for recycling back through the tubes to the freezing operation. In the thawing phase of operation the refrigerant surrounding tubes 2 may be displaced or heated to thaw loose the ice rods in the tubes thus allowing them to drop to a severing mechanism which severs the ends of the rods as they

project from the tubes. The severing mechanism is enclosed in a chamber 4 below the ends of the tubes and this chamber has a side opening or port 5 adjacent to the bottom for discharge of ice therefrom.

Referring to FIG. 2, the bottom plate or tube head 3 of the freezer or evaporator is centrally bored and threaded to receive a threaded stud 7 upon which is located a bearing sleeve 8. Surrounding this sleeve is a flanged bushing 9 of antifriction material, of somewhat shorter length than the sleeve, pressed into the hub 11; and the sleeve 8 is clamped against the bottom plate of the freezer by a washer 12 and locking nuts 13. The washer 12 thus retains the bushing 9 and hub 11 against removal and allows the bushing and hub to rotate freely on the sleeve. An annular rim 14 having a V-groove 15 on its periphery is secured to the central hub 11 by a plurality of plates indicated by the numbers 16, 17, 18, and 19 which may be welded to the hub and rim, or are secured in place in any other desired manner. The rim, plates and hubs thus are suspended from the tube head 3 and are rotated by a V-belt 21 passing around the rim in the groove and around a V-groove pulley 22 driven by the motor 23.

The upper most plate 16 may be substantially flush with the upper edge of the rim 14 and its forward or leading edge (when rotating in the direction of the arrow in FIG. 3) is recessed to receive a relatively sharp edge blade 25, and its rear or opposite edge is relatively blunt. The lowermost plate 17 has its rear edge sufficiently close to blade 25 in vertical projection so that the plate acts as a gauge to support the ice rod while it is severed by the blade 25. Plate 18 lies in a plane above plate 17 and below plate 16. Similarly, plate 19 lies in a plane above plate 18 and below plate 16. The stepped plates allow the ice rods to be lowered in steps when the severing device rotates in forward or cutting direction until they reach plate 17 where they are severed by blade 25.

The hub 11 of the cutter (FIG. 2) has a flange 41 welded thereto and a tubular extension 42 having an upper flange 43 secured thereto. The lower edge of the tubular extension 42 has keyed therein a shaft 60 which is secured to circular member 44 by locking nuts 61. Shaft 60 extends through hub 63 and has a shoulder 62 which separates the circular receiving, propelling and classifying member 44 from the tubular extension 42. Thus the receiving, propelling and classifying member 44 is secured to the tubular extension 42 and is revolved at the same speed by the V-belt 21 of motor 23. A deflector member indicated generally by the numeral 46 comprises a semicircular bearing portion 47 secured to a plate 48. The plate 48 extends across the circular member 44 to terminate just above the edge of the discharge port 5, the end of the plate being designated by numeral 52. The plate assembly is connected by welding or other suitable means to a strap bracket 51 which supports the entire assembly to relieve the plate so that space is provided between the bottom and the circular member 44 to eliminate wear and noise. The discharge port 5 connects with chute 53 and the chute leads to insulated bin 55 for storage of ice. A grille 57 may be interposed adjacent the discharge port 5 to allow water passing through the tubes to pass therethrough into the water tank 45 for recirculation. If desired, a deflector plate 58 may be provided between the port 5 and the severing device. This deflector directs water and falling ice away from port 5 to prevent entrance of water into the storage bin. Deflector 58 directs the cubes falling at this point onto the member 44 so as to be retained thereon for classification prior to being discharged through port 5.

Referring now to FIG. 3, the receiving, propelling and classifying member consists of a hub 63 to which radiating ribs 64 are attached by welding or other suitable means. Each of the ribs is curved outwardly and rearwardly (relative to the direction of rotation of the 75

hub 63), in the form of a large arc, so as to terminate at a point 65 at the periphery of the circular member. The ends of the ribs are welded or attached by other suitable methods to an outer rim or ring 66 which is located below the ribs 64 so as to prevent obstruction to the propulsion of the ice cubes therefrom. As is illustrated in FIG. 3 there may be provided reinforcing spokes 67 which are welded at various points to each of the ribs which they contact.

A modified form of the receiving, classifying and propelling device is illustrated in FIG. 4 in which each of the ribs is attached to the hub so that the distance 69 between adjacent ribs increases progressively as the ribs approach the periphery and are welded to the outer ring 66 at point 65. In this embodiment, the ribs 64 are welded to intermediate ring 68. The only criterion is that the widest distance 69 between adjacent ribs be less than the outer dimension of the ice cubes. This is true since in the large commercial icemaking machines the circular member 44 may be 36 inches or larger in diameter. In such instances the form of circular member shown in FIG. 3 is desired since the distance 69 between the adjacent ribs 64 is practically the same throughout. The relation of the ice cube 70 and the ribs 64 is illustrated in the detailed drawing in FIG. 5. It will be noted that the ribs act as tracks for the ice cube retaining it thereon (allowing the undersized particles and fines to drop through to the cold water tank), and directing it along a specified path to the periphery of the member. In conjunction therewith, the deflector plate 48 mounted across the circular member 44 coacts with said rotating member to impress a reaction force on the cubes to propel them through said path and through the port 5 into chute 53 and thus into the insulated bin 55.

To recapitulate the operation of the apparatus, at the end of the freezing cycle the freezer tubes are heated in known manner and gravitationally release the ice rods which fall through the lower ends of the tubes and rest upon the plates 16, 17, 18 and 19. Assuming the rotation in the direction of the arrow shown in FIG. 3, those ice rods which rest upon plates 17 (which acts as a gauge) will be engaged by the cutter blade 25 and will be severed by cutting, shearing or breaking action.

As the severing member rotates the rods resting on plate 18 will drop onto the plate 17 and will be cut off or broken by the cutter blade 25 that is brought against them. The ice cubes will drop onto the circular member 44. As the circular member 44 rotates with the cutter the cubes are carried around the plate and rest upon the ribs 64 which act as tracks to propel the cubes through the path defined by said ribs. Undersized fragments and ice chips will fall to the cold water tank 45 and will be effectively separated from the cubes. As the cubes rotate with the tracks they engage with the deflector member 46 and their motion relative to the tracks pushes them through a predetermined path, rearwardly, relative to the direction of rotation, to the periphery of said circular member 44 and out of the port 5 onto the chute 53 and thence into ice storage bin 55.

Various modifications can be made in the supporting structure for the ribs and they may be designed so as to lie substantially equidistant from each other or in such manner that the distance between ribs progressively increases as the distance from the hub increases. The only criterion is that the distance 69 between the ribs be less than the minimum outer dimension of acceptable ice cubes, so that all other ice fragments drop through the tracks.

What I claim is:

1. In a machine for producing cut ice cylinders and including a severing member for cutting ice rod into sized pieces:

(A) a rotating receiving, classifying and propelling device, for receiving the cut ice cylinders, separating the cut ice cylinders from undersized ice pieces and

for propelling the sized ice cylinders in a curving path, relative to said device, and toward the periphery of the device to a discharge port, which comprises:

- (1) a circular member comprising a hub and a plurality of ribs radiating from said hub;
- (a) each of said ribs being attached to said hub and curving outwardly and rearwardly from the point of attachment, relative to the direction of rotation of said hub and terminating at the periphery of said circular member,
- (b) said ribs forming spaced tracks for said cylinders, said tracks acting to support, guide and restrain said cylinders against centrifugal force and undesired random movement in a plane perpendicular to the axis of rotation of said hub and to define a path for said cylinders rearwardly, relative to the direction of rotation of said hub, and toward the periphery of said circular member,
- (c) the distance between said tracks being less than the minimum outer dimension of said ice cylinders,
- (2) a housing surrounding said circular member and containing a port for discharge of said cylinders; and
- (3) a deflector, fixedly mounted above and across a portion of said circular member and extending from said hub to a point in proximity to said port,

(a) said deflector coacting with said rotating member and imposing a reaction force on said cut ice cylinders to propel said cylinders along the path defined by said tracks to the periphery of said member and through said port.

2. A receiving, classifying and propelling device as defined in claim 1 in which:

- (A) each of said ribs is mounted substantially parallel to its adjacent ribs so that the distance between pairs of ribs is substantially the same at any point from the hub.
